HAIRPIN SPREADER

Theodore L. Unruh, Los Angeles, Calif.

Application April 20, 1951, Serial No. 14,906

Term of patent 14 years

(Cl. D86—3)

To all whom it may concern:

Be it known that I, Theodore L. Unruh, a citizen of the United States, residing at 160 North Beau-
dry Ave., in the county of Los Angeles and State of California, have invented a new, original, and ornamental Design for a Hairpin Spreader, of which the following is a specification, reference being had to the accompanying drawing, forming part thereof.

Figure 1 is a view in front elevation of a hairpin spreader embodying my new design;

Figure 2 is a top plan view of the hairpin spreader; and

Figure 3 is a view in perspective showing the hairpin spreader.

I claim:

The ornamental design for a hairpin spreader, substantially as shown.

THEODORE L. UNRUH.
